WRENCH

Lawrence C. Newberry, Long Beach, Calif.

Application March 31, 1943, Serial No. 481,309

4 Claims. (Cl. 81—102)

This invention relates to a wrench, especially one capable of use either as a pipe wrench or as a monkey wrench.

It is aimed to provide a construction which is quickly adjustable, durable, and efficient and which especially has a saddle slidably mounted on one jaw carrying the other jaw for tooth engagement with the first jaw, to which second jaw a handle is pivoted as well as to the saddle and on which the wedge lock is slidably mounted to coat with the handle and the second-mentioned jaw.

The more specific objects and advantages will become apparent from the description following taken in connection with accompanying drawings illustrating an operative embodiment.

In said drawings:

Figure 1 is a view in elevation of a wrench constructed in accordance with the invention;

Figure 2 is an edge view of said wrench;

Figure 3 is an enlarged view of the major portion of the wrench, parts being in section to disclose details;

Figure 4 is a view of the parts similar to Figure 3 but in position gripping a pipe;

Figure 5 is a cross section taken on the line 5—5 of Figure 4;

Figure 6 is a detail section taken on the line 6—6 of Figure 3; and

Figure 7 is a detail section taken on the line 7—7 of Figure 3.

Referring specifically to the drawings wherein like reference characters designate like or similar parts, a U-shaped saddle is provided at 10 which approximately houses the main jaw or block 11. A pin 12 bridges the side walls of the saddle and passes through an enlarged opening 13 in jaw block 11. The latter will move longitudinally with the saddle, but is capable of movement toward and away from the bridge of the saddle.

The outer or movable jaw generally designated 14 also is mounted by the saddle 10, having a shank 15 passing slidably through the saddle between its bridge and the jaw block 11. Jaw 14 has a head at 16 provided with teeth or serrations at 17 to coat with opposed teeth or serrations 18 on the jaw block 11. The inner longitudinal face of the shank 15 has ratchet teeth or serrations at 19, while the opposed face of the jaw block 11 has similar ratchet teeth or serrations at 20.

Normally the teeth 19 and 20 are disengaged and spaced as shown in Figure 3, as spacer pins 21 are slidably mounted in recesses 22 in the jaw

block 11, against the expansive action of coil spring 23. The outer or free ends of the spacer pins 21 are preferably spherical and abut the teeth 19 and are freely slideable thereover, preventing, normally, contact of the teeth 20 with the teeth 19.

The free end of shank 15 is recessed and fitted therein with a stop element 25, a screw 26 securing it in place. This stop element is adapted for abutment with the bridge of the saddle 10 to prevent accidental detachment of the movable jaw 14 from the saddle and vice versa.

The handle of the wrench is shown at 27, and it is pivoted by a pin 28 to said saddle 10. The inner end of said handle 27 extends into a recess 29 provided in one end of the jaw block 11 and at 30 said end of the handle 27 is pivotally connected to the jaw block. It will be noted that there is sufficient clearance between the inner end of handle 27 and the walls of the recess 29 to enable the handle 27 to be rocked on the pivot 28 and move the block into and out of position where the teeth 20 thereof engage and disengage those at 19.

In order temporarily to lock the jaw blocks 11 and 14 in adjusted position with their teeth 20 and 19 engaged, a slide 31 is provided. This slide is dovetailed at 32 in order to slidably fit a dovetailed or undercut groove 33 provided in one edge of the operating lever or handle 27. One end of the slide 31 has a wedge 34 thereon and the other end is enlarged at 35 to provide a fingerpiece.

Normally the movable jaw 14 and main jaw 11 are free to slide to different adjustments in order to engage work such as a pipe P shown in Figure 4. Such adjustment is quickly attained since the jaw 11 is moved through longitudinal movement of the handle 27 or the jaw 14 is longitudinally moved relatively thereto. When the desired adjustment is attained, handle 27 is rocked on the lever 28, thereby through its pivotal connection at 30 with the jaw 11 sliding the latter toward the shank 15 and engaging the teeth 19 and 20, with the pins 21 receding into the recesses 22 and compressing the spring 23, following which, the slide 31 is moved along the handle 27 and the wedge 34 thereof is brought into engagement with the adjacent wall of the recess 29 so that the jaw 11 will be locked in the position mentioned and the lever 27 will be locked against movement on the pivot 28. Thereupon the handle 27 is moved in the usual manner of a pipe- or monkey-wrench with respect to the work P. It is clear that the wrench is capable of use as both a monkey wrench and a pipe wrench.

Various changes may be resorted to provided that they fall within the spirit and scope of the invention.

I claim as my invention:

1. A wrench comprising a saddle, a jaw slideable therein, a jaw block, means mounting the jaw block for movement with the saddle and for movement independently of the saddle into and out of engagement with the jaw, said jaw block having a recess, a lever pivoted to the jaw block within the recess and to the saddle operative to effect the last-mentioned movement, and means to secure the handle and block against relative movement when the block is engaged with the jaw, comprising means slidable into the recess to bridge the space between the lever and the opposed wall of the recess.

2. A wrench comprising a saddle, a jaw slideable therein, a jaw block, means mounting the jaw block for movement with the saddle and for movement independently of the saddle into and out of engagement with the jaw, said jaw block having a recess, a lever pivoted to the jaw block within the recess and to the saddle operative to effect the last-mentioned movement, and means to secure the handle and block against relative movement when the block is engaged with the jaw, comprising means slidable into the recess to bridge the space between the lever and the opposed wall of the recess consisting of a wedge slidably mounted on the lever.

3. A wrench comprising a saddle, a jaw slideable therein, a jaw block, means mounting the jaw block for movement with the saddle and for movement independently of the saddle into and

out of engagement with the jaw, a lever pivoted to the saddle and to the jaw block operative to effect the last-mentioned movement, and means to secure the handle and block against relative movement when the jaw and jaw block are engaged whereby the jaw and jaw block will be locked together, consisting of a wedge means slidably mounted on the handle, the block having a recess into which the wedge means extends and the wedge means being of dovetail cross section engaged in a groove of similar shape in the handle.

4. A wrench comprising a saddle, a jaw slideable therein, a jaw block, means mounting the jaw block for movement with the saddle and for movement independently of the saddle into and out of engagement with the jaw, a lever pivoted to the saddle and to the jaw block operative to effect the last-mentioned movement, means to secure the handle and block against relative movement when the jaw and jaw block are engaged whereby the jaw and jaw block will be locked together, consisting of a wedge means slidably mounted on the handle, the block having a recess into which the wedge means extends and the wedge means being of dovetail cross section engaged in a groove of similar shape in the handle, a pin spanning the saddle, the jaw block having a slot through which the pin extends, interengageable teeth between the jaw and jaw block, and spring-pressed means on one of said parts normally engageable with the other and the teeth thereof to prevent interengagement of the teeth.

LAWRENCE C. NEWBERRY.
